Primary Examiner — George D Kirschbaum*Assistant Examiner* — Jennifer Watkins*(74) Attorney, Agent, or Firm* — Stetina Brunda Garred and Brucker(57) CLAIM

The ornamental design for a sock, as shown and described.

DESCRIPTION

FIG. 1 is a front perspective view of a pair of sock of the present invention showing my new design,

FIG. 2 is a top plan view thereof;

FIG. 3 is a right side elevational view thereof;

FIG. 4 is a front view thereof;

FIG. 5 is a bottom plan view thereof;

FIG. 6 is a left side elevational view thereof; and,

FIG. 7 is a rear view thereof.

The evenly dashed broken lines showing a human foot and a left foot sock are for the purpose of illustrating environment and form no part of the claim. The evenly dashed broken lines on the sock are for the purpose of illustrating stitching and form no part of the claim.

1 Claim, 3 Drawing Sheets(56)
